ROLLING MACHINE OF THE BRIDGE TYPE
FOR THE TREATMENT OF LEATHER

Josef Kadlecik, Spytihnev, Czechoslovakia, assignor to Svit, narodni podnik, Gottwaldov, Czechoslovakia

Application October 18, 1949, Serial No. 122,006
In Czechoslovakia October 30, 1948

5 Claims. (Cl. 69—46)

1

The present invention relates to improvements in rolling machines of the bridge type used for ironing or rolling leather, and more particularly to an arrangement which provides for an easy control both of the reversal of the working roll and of the length of the rolling stroke of the latter.

For the treatment of leather, especially of sole leather in the shoe manufacture, rolling machines are employed in which the leather is rolled or ironed by means of heavy roll to which a reciprocating movement is imparted. The reversal in the travel of the roll is effected by means of a shifting rod which at a suitable moment shifts, for instance, a belt of the machine drive. The shifting rod is actuated in the majority of constructions automatically by the roll slide abutting against stops fastened on the shifting rod. The distance between the end positions of the roll is determined by adjustment of the stops.

In the drive of rolling machines, shifting devices of various designs have been proposed for reversing the travel of the roll in accordance with the actual length of the leather piece under treatment. In one of the prior designs the slide is provided with a clamping device which upon the depression of a pedal seizes the shifting rod at the appropriate moment and moves the latter so as to reverse the direction of movement of the roll. According to another prior construction the driving spindle of the slide drives also a pulley, which by means of a loosely running belt is connected to a second pulley provided with a toothed gear adapted to mesh with a rack formed on the shifting rod. By depressing a pedal at the appropriate moment the belt is tensioned thereby actuating the shifting device.

Both these arrangements show certain disadvantages which reside primarily in that the shifting devices require the constant attention of an attendant and for safety grounds they require also the use of automatic end stops which cause the shifting to be effected automatically in the extreme positions of the roll. The handling of the machines of this type is very fatiguing for the attendant because at each reversal of the travel of the roll he must depress the pedal and, in addition, tension the clamping device or shift the belts by muscular force.

Further on stops have been proposed having contact elements which under the pressure of the oncoming slide cause the stops to be fixedly connected to the shifting rod for the time

2

during which the slide exerts pressure against the contact element.

However, all the prior designs have a common disadvantage in that they are relatively complicated and for this reason require careful maintenance and relatively frequent repair.

This disadvantage is completely avoided by the present invention which resides in that the shifting rod has fixed thereon step-like stops which are grouped into two helices arranged in opposite relationship to each other with respect to the center point of the rod.

For a better understanding of the essence of the present invention a constructional example will be described hereinafter with reference to the accompanying drawings in which

Figure 1 is an over-all rear view of a bridge rolling machine according to the present invention;

20 Figure 2 shows the arrangement of the stops in developed form;

Figure 3 is a detail view showing the shifting rod with the helically arranged stops on the same; and

25 Figure 4 is a diagrammatic view of the shifting device together with its hand operated control rod.

In the machine shown in the drawings, the overhead beam 3 has suspended on the same between the two stays 1 and the reinforcing bolts 2 a slide 4 which is adapted to be moved to and fro together with the working roll 5. The slide 4 is driven by a screw threaded spindle 6 to which is imparted from a motor 7 through the intermediary of a bottom counter shaft 8 and a top countershaft 9, a straight belt 10, a crossed belt 11 and the wedge-shaped belts 12. The two belts 10 and 11 run round loose pulleys 13 and 14 while the intermediate pulley 15 is fast on the shaft 9 and by means of the wedge-shaped belts 12 is connected to the driving spindle 6. The movement and direction of rotation of the pulley 15 which is fast on its shaft are determined in each case by the position of the belt fork 16, shifting link 17, lever 18 and shifting rod 19.

In accordance with the present invention, fixed stops 20 are provided on the shifting rod 19. Figure 3 shows that the stops 20 are arranged along two opposed helices, as viewed from the center point of the shifting rod 19, the developed shape of the two helices being shown in Figure 2. The stops 20 form an integral unit with the shifting rod 19. The slide 4 carries two spring urged contact elements 21 which upon engagement with the positioned stops 20 produce longi-

tudinal movement of the shifting rod 19 and thereby reversal of the operation of the machine.

The shifting rod 19 is mounted in bearings 22, Figure 4, at the rear of the machine and through the intermediary of a chain transmission 24 is connected to a hand operated control rod 25 which is carried in bearings 23 on the front side of the machine so as to be readily accessible from the working station.

The apparatus above described operates as follows:

In accordance with the length of the leather piece to be rolled, the attendant first adjusts the operating stroke of the roll 5 by turning the control rod 25, about its longitudinal axis whereby the corresponding pair of stops 20 is positioned opposite to the contact elements 21. The stops are grouped on both sides of the center point of the shifting rod into two helices in such a way that the two corresponding opposite stops nearest to each other serve to limit the shortest working stroke of the roll, while the two stops which are most remote from each other serve to limit the largest working stroke of the roll (Figure 2). Depending on the number of pairs of stops in the helices, a finer or a rougher adjustment of the stroke of the working roll is obtained, the stroke being determined by the surface area of the leather piece to be rolled. The working roll which travels over the leather will engage by means of the contact elements 21, Figure 1, with a positioned stop 20 and will displace the shifting rod 19 as a whole in the direction of its longitudinal axis whereby the single armed lever 18 is caused to rock and thereby through the intermediary of the shifting link 17 and the fork 16 formed on the latter, to shift, for instance, the straight belt 10 on to the fast pulley 15 so that the latter which hitherto was rotated by the crossed belt in a given direction, is now rotated by the straight belt in the opposite direction. As a consequence, the driving spindle 6 is rotated also in a direction opposite to that of its preceding rotation and the slide with the working roll is caused to travel towards the opposite stop. Should the attendant wish to alter the size of the working stroke of the roll 5 during the operation of the machine, he only must turn the hand operated rod 25 so as to position on the shifting rod, which is connected by means of the chain transmission 24 with the hand operated rod, the corresponding pair of stops and thereby to determine exactly the required stroke of the working roll.

The apparatus according to the present invention provides a simple, readily performable and very reliable method for controlling the movement of the working roll.

5. What I claim is:

1. In a rolling machine of the bridge type having a reciprocating working roll the direction of movement of which is changed by means of a shifting rod provided with stops which limit the working path of the roll, the arrangement on the shifting rod of fixed stops which are disposed along two opposed helices as viewed from the center point of the said rod.

2. In a rolling machine of the bridge type having a reciprocating working roll the direction of movement of which is changed by means of a shifting rod provided with stops which limit the working path of the roll, the arrangement on the shifting rod of fixed stops which are disposed along two opposed helices as viewed from the center point of the said rod, and a control rod for controlling the rotational movements of the shifting rod.

25 3. In a rolling machine of the bridge type having a reciprocating working roll the direction of movement of which is changed by means of a shifting rod provided with stops which limit the working path of the roll, the arrangement on the shifting rod of fixed stops which are disposed along two opposed helices as viewed from the center point of the said rod, and a control rod for controlling the rotational movements of the shifting rod, the control rod and the shifting rod being arranged parallel to each other.

35 4. In a rolling machine of the bridge type having a reciprocating working roll the direction of movement of which is changed by means of a shifting rod provided with stops which limit the working path of the roll, the arrangement on the shifting rod of fixed stops which are disposed along two opposed helices as viewed from the center point of the said rod, and a control rod for controlling the rotational movements of the shifting rod, the control rod and the shifting rod being arranged parallel to each other and connected together by means of a transmission gear.

40 5. The rolling machine of the bridge type as set forth in claim 4, in which the control rod is connected to the shifting rod by means of a chain transmission.
